UNITED STATES PATENT OFFICE.

EDWIN COULSON CLARK, OF CANTON, AND ARTHUR T. BROWER, OF CLEVELAND, OHIO.

TONE MODIFIERS FOR PHONOGRAHS.

Application filed November 20, 1922. Serial No. 602,045.

To all whom it may concern:

Be it known that we, EDWIN C. CLARK, a subject of the King of Great Britain, and ARTHUR T. BROWER, a citizen of the United States, residing at Canton and Cleveland, in the counties of Stark and Cuyahoga, respectively, and State of Ohio, have invented certain new and useful Improvements in Tone Modifiers for Phonographs; and we do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to tone modifiers for phonographic machines and has for an object to provide a device interposed between the usual stylus and stylus arm, by which the vibrations delivered by the stylus arm to the sound box diaphragm will be varied from the normal vibrations to thereby produce modification of the tone delivered from the amplifier.

A further object of the invention is to provide a device interposed between the usual stylus and stylus arm of a phonographic instrument, which comprises a cushioning element interrupting all metallic connection between the stylus and the stylus arm and substituting therefor a yielding, elastic and resilient member.

35 A further object of the invention is to provide a device embodying a spindle adapted to be employed in association with the stylus arm of a sound box in substantially the usual and ordinary manner, with a stylus located in axial alinement with the spindle, but wholly separated therefrom metallically by the interposition of a cushioning substance providing for yielding of the parts in all directions.

45 A further object of the invention is to provide means for varying the tension upon the cushioning parts whereby in the same device a modification of the tone may be accomplished.

50 With these and other objects in view the invention comprises certain novel parts, units, elements, combinations, inter-actions and functions, as disclosed in the drawings, together with equivalents thereof, as will

be hereinafter more fully described and 55 claimed.

In the drawings:

Figure 1 is a view of a conventional sound box in side elevation with the present modifying attachment connected therewith in operative position;

Figure 2 is a view in longitudinal diametrical section through one type of the modifier, which at present is believed to be 60 the preferred type;

Figure 3 is likewise a sectional longitudinal diametrical view through a modifier of slightly different construction;

Figure 4 is a detail view in side elevation of the several component elements of a modifier of the type shown at Figure 3.

Like characters of reference indicate corresponding parts throughout the several views.

It is well known that phonographs embody a diaphragm shown conventionally at 10 forming a part of the sound box 11 having a stylus arm 12 connected therewith fulcrumed in some manner, as indicated at 13. Ordinarily a stylus or needle is secured directly to this stylus bar by means of the thumb screw 14 or some equivalent or substitute instrumentality. This produces a metallic continuity from the stylus to the stylus arm so that the vibrations of the stylus from 85 its engagement with the record 15 are communicated faithfully to the diaphragm 10.

It is also well known that this results in imparting to the diaphragm 10 and reproducing through the amplifier those surface 90 sounds ordinarily known as scratching. The present invention embodies a spindle 16 of the size and general proportion to be engaged by the stylus bar, as is ordinarily done by the engagement by the stylus. This spindle 16 is preferably headed, as indicated at 17 and is set into a socket member and surrounded wholly by cushioning material.

In the type shown at Figure 2 an externally screw-threaded socket member 18 is employed having a sleeve 19 internally screw-threaded to fit thereover. The socket member 18 is provided with an arm 20 having an opening therein to receive the stylus 21 with means for clamping the stylus in 105 position, shown as the thumb screw 22, similar to the thumb-screw 14. It is to be understood, of course, that the specific mechanical

means represented by the thumb screw 22 is no limitation upon any other mechanical means for maintaining the stylus 21 in its operative relation to the arm 20.

5 Within the socket member 18 a disk 23 is employed upon which the head 17 rests. The spindle itself is surrounded by a cushion 24 with an annulus 25 above said cushion provided with a boss 26 extending upwardly

10 through an opening 27 in the sleeve 19.

In the type shown at Figure 3 all the parts are identical except that the socket member 18' is internally threaded and the compression member 19' is externally screw-threaded.

15 It will be apparent from either Figures 2 or 3 that the spindle 16, including its head 17 is wholly surrounded within the member by a cushioning material. This cushioning 20 material, as at present practised, is rubber, but it is to be understood that the invention is in no way limited to the employment of rubber for the purpose and that any other cushioning material found desirable or efficient for the purpose is fully within the 25 scope of the invention.

In operation the device is assembled as shown either at Figures 2 or 3 according to the type employed, the spindle 16 being 30 inserted into the stylus bar in the manner usually employed in inserting and securing a stylus and will there remain. The stylus 21 may be changed as often as the exigencies of use may make desirable.

35 It is also apparent that by exerting greater or less pressure upon the cushioning members by the manipulation of the threaded connection between the two parts 18 and 19 or 18' and 19', the elasticity of connection 40 will be varied, thereby varying the vibration transmission of the device from the stylus to the stylus bar.

45 It will also be obvious that while the cushioning of the spindle has been shown as composed of several parts separately united and connected that these parts may be varied as to their relative sizes or shapes and that the employment of three separate elements for the purpose is the present practice,

probably not essential to the invention and 50 that any manner of completely cushioning the spindle 16 relative to the stylus-carrying metallic parts is comprehended within the present invention whether said cushioning be in a lesser or greater number of 55 parts or formed as a single cushion with the head 17 of the spindle embedded, such features being merely mechanical carrying forward of the present invention and to be dictated by circumstances and contingencies 60 of manufacture and marketing demand.

Also the specific type of socket members and other mechanical features while represented in the drawing in a form at present seeming desirable, are obviously capable of 65 variation within the scope of the present invention.

What we claim is:

1. A tone modifier for phonographs comprising a hollow member, a spindle having 70 one end inserted into the hollow member, cushioning material embracing said inserted end and maintaining it out of metallic contact with said hollow member, said hollow member being also provided with a stylus-receiving socket in alinement with said spindle.

2. A tone modifier for phonographs comprising a socket member embodying a stylus socket and a chamber filled with compressible cushioning material, a spindle extending into the chamber and embedded in the cushioning material, and a closure for the chamber adapted to exert varying degrees of compression on the cushioning material. 80

3. A tone modifier for phonographs, comprising a socket member embodying a stylus socket and a chamber filled with compressible cushioning material, a spindle extending into the chamber and having a head embedded in cushioning material, and a closure for the chamber adapted to exert varying degrees of compression on the cushioning material. 85

90 In testimony whereof we hereunto affix our signatures.

EDWIN COULSON CLARK.
ARTHUR T. BROWER.
